UNITED STATES PATENT OFFICE

JACOB W. ROLLE AND FREDERICK M. PLATH, OF PHILADELPHIA, PENNSYLVANIA

WINDOW FRAME

Application filed October 21, 1930. Serial No. 490,121.

The principal object of the present invention is to provide a window frame at a window sash and a screen and ventilator and in which the screen and ventilator may be stored beneath the window frame, leaving the sash frame free for raising and lowering and in which either or both the ventilator frame and screen frame may be selectively and conveniently connected with the sash frame and by it brought into position to cover the window opening. Another object of the invention is to provide convenient and efficient manual means at the sash frame for selectively connecting it to and disconnecting it from either or both of the other frames. Another object of the invention is in such a structure to prevent moisture from entering the well or compartment in which the ventilator and screen frame are stored. Another object of the invention is to provide efficient ways in which the various parts slide.

Other objects of the invention will appear from the following description at the end of which the invention will be claimed.

Generally stated, the invention comprises a window frame having a well arranged beneath its sliding sash frame and having a sliding ventilator frame and a sliding screen frame both adapted to occupy the well in side by side relation, together with manually operable means at the sash frame and adapted to selectively connect the sash frame with the other frames.

The invention also comprises the improvements to be presently described and finally claimed.

In the accompanying drawings

Figure 1 is an elevational view, looking from the inside of a window frame, embodying features of the invention.

Fig. 2 is a transverse sectional view of the same.

Fig. 3 is a front view drawn to an enlarged scale of the lower portion of the frame with parts removed.

Fig. 4 is a transverse section on the line 4-4 of Fig. 3.

Fig. 5 is a perspective view of one of the elements of the screen frame.

Fig. 6 is a transverse sectional view illus-

trating the ways in which the parts slide, and

Fig. 7 is a transverse sectional view of the lower portion of the ventilator frame.

Referring to the drawings 1 is a window frame having a well or box-like structure 2 open at the top and arranged beneath the sliding frame 3. The well may be of metal and concealed within the wall beneath the window and its open top is aligned with the sliding sash frame 3. 4 is a sliding ventilator frame, and 5 is a sliding screen frame, and they are both adapted to occupy the well in side by side relation, as indicated in Fig. 4. 6 indicates means manually operable at 65 the sash frame and adapted to selectively connect the sash frame with the other frames so that when the sash frame is raised, the ventilator frame, being connected with it, is raised to cover the window opening, as indicated in 70 Fig. 1, or, if desired, the sash frame 5 may be similarly connected, or, if preferred, both ventilator and screen frames may be raised with the sash to cover the window opening. As shown the means 6 comprise a turnable 75 knob 7 having oppositely disposed spaced hooks 8 and 9 arranged in a groove 10 provided in the sash frame, and studs 11 and 12 on the other two frames and projecting into the groove 10. When the hook 8 engages the 80 stud 11, the sash frame 3 and screen frame 5 are connected. When the hook 9 engages the stud 12, the sash frame and ventilator frame 4 are connected. When the hooks are in the 85 position shown in Fig. 3, the sash frame 3 is disconnected from all the other frames. By way of further description, the letters S, N and V indicate how to turn the knob to screen engaging position, to neutral position out of engagement with either ventilator or screen 90 frames, and to ventilator frame engaging position. As shown there are two of these engaging means 6, and one of them may be turned to connect the sash frame and ventilator frame, and the other may be turned to connect the sash frame and screen frame, so that when the window is raised, both the screen and ventilator frames are positioned to cover the window opening. The guides or ways which will be described are useful in 95 100

permitting both ventilator and screen frames to be raised by the sash frame.

Referring to Fig. 6, the guides or ways comprise four ribs 13, 14, 15 and 16, which may be provided by crimping a strip of metal. The rib 14 serves to guide the ventilator frame 4, the rib 15 serves to guide the screen frame 5, and the outside ribs 13 and 16 serve to guide the sash frame 3. The flap 17 serves to exclude water from the well or box 2, and it may be provided as an extension of the element or stamping 18 of the ventilator frame, which element or stamping may also well carry the stud 12. At the bottom of the ventilator frame, Fig. 7, there is provided a spring pressed pivotal shutter 19 adapted to exclude water from the well 2 when the frame 4 is in elevated position. The stud 11 may be carried by a fitting 20, a portion of which underlaps the strip 21, and the strip 21 also overlaps a strip 22 on the screen frame.

It will be obvious to those skilled in the art to which the invention relates that modifications may be made in details of construction and arrangement and matters of mere form without departing from the spirit of the invention which is not limited to such matters or otherwise than the prior art and the appended claims may require.

30 We claim:

1. In a window frame having a well beneath a sliding sash frame and having a sliding ventilator frame and a sliding screen frame both adapted to occupy the well in side by side relation, the combination of single means manually operable at the sash frame and adapted to selectively connect the sash frame with the other sliding frames.

2. In a window frame having a well beneath a sliding sash frame and having a sliding ventilator frame and a sliding screen frame both adapted to occupy the well in side by side relation, the combination of a manually turnable handle having oppositely disposed spaced hooks arranged in a groove provided in the sash frame, a stud on the screen frame projecting into said groove and arranged to be engaged and disengaged by one hook, and a stud on the ventilator frame projecting into said groove and arranged to be engaged and disengaged by the other hook, whereby the sash frame may be connected to and disconnected from either of the other sliding frames.

55 3. In a window frame having a well beneath a sliding sash frame and having a sliding ventilator frame and a sliding screen frame both adapted to occupy the well in side by side relation, the combination of a pair of manually turnable handles each having spaced hooks, a pair of studs on the screen frame, and a pair of studs on the ventilator frame, whereby one hook relating to one handle may engage the ventilator frame and one hook relating to the other handle may engage

the screen frame to operate the last named two frames at the same time.

4. In a window frame having a well beneath a sliding sash frame and having a sliding ventilator frame and a sliding screen frame both adapted to occupy the well in side by side relation, the combination of means manually operable at the sash frame and adapted to selectively connect the sash frame with the other sliding frames, said ventilator frame provided at the top with a flap and at the bottom with a hinged shutter.

5. In a window frame having a well beneath a sliding sash frame and having a sliding ventilator frame and a sliding screen frame both adapted to occupy the well in side by side relation, the combination of means manually operable at the sash frame and adapted to selectively connect the sash frame with the other sliding frames, said window frame provided with four ribs of which the outside ribs cooperate with the window sash and of which one of the other ribs cooperates with the ventilator frame and the other with the screen frame.
